UNITED STATES PATENT OFFICE.

CHARLES L. GEORGE, OF FINDLAY, OHIO, ASSIGNOR TO THE BUCKEYE TRACTION DITCHER COMPANY, OF FINDLAY, OHIO, A CORPORATION OF OHIO.

BUCKET CLEANER FOR TRENCHING MACHINES.

Application filed December 30, 1927. Serial No. 243,535.

This invention relates to a bucket cleaner adapted to be used on trenching machines, and more especially on those of the type having an endless series of continuously traveling digging and conveying buckets.

The general object of the invention is to provide improved means for cleaning or scraping muck, gumbo or other sticky material from the bucket as the latter is carried past dumping position during its travel. Co-operating with this cleaning means, a device is provided which permits the cleaner to swing inwardly out of the way of the bucket when it meets with an unusual obstruction, which would otherwise be apt to cause damage to the machine.

The specific construction of the invention, together with the objects and advantages thereof, will be more particularly explained in the following detailed description taken in connection with the accompanying drawings, which illustrate one embodiment thereof.

In the drawings—

Figure 1 is a vertical longitudinal section through the rear portion of a trenching machine with the bucket cleaner secured in operative position thereon, a portion of the housing being broken away to illustrate more clearly the interior construction of the cleaner.

Fig. 2 is a detail sectional view taken on the line 2—2 of Fig. 1.

Fig. 3 is a rear end view of the cleaner and the adjacent portion of the machine.

Fig. 4 is a section taken approximately on the line 4—4 of Fig. 3.

The trenching machine with which the bucket cleaner is used comprises a rearwardly and upwardly extending beam or framework 6 at the rear end of which a transverse shaft 7 is journaled. The shaft 7 is driven by means of a sprocket wheel 8 secured centrally thereof, and a sprocket chain 9 engages the sprocket wheel 8 and is driven by any suitable means. Wheels 10 of suitable construction are secured to the shaft 7 near the end thereof and over these wheels 10 pass conveyor chains 11. Digging and conveying buckets 12 are secured to certain links of the chains 11 at suitably spaced intervals. These buckets are of well known construction and are adapted to dig into the ground as they reach the lowermost part of their orbit and to dump rearwardly as they are carried about the rear wheels 10.

Brackets 13 are secured to the rear end of the beam 6 and are formed with bearing boxes for the shaft 7. A casting 14 is secured for longitudinal adjustment on the brackets 13 by means of bolt and slot connections 15 and 60 constitutes a support and housing for the bucket cleaning device which constitutes the subject matter of the invention.

The bucket cleaner comprises a plurality of spring 16 each made up of a plurality of 65 leaves firmly secured together and mounted within a clip 17 which is pivoted at 18 to the rear portion of the casting 14. The leaves of each spring are curved outwardly at their rear ends as shown at 19, and each successive 70 leaf is a little longer than the one behind it. The several springs are so arranged that they will scrape the bottom of each bucket 12 as it passes about the wheel 10, leaving the bucket comparatively clean. The springs are separated from each other by flanges 20 formed within the housing.

The leaves of the springs are comparatively stiff, yet will ordinarily yield sufficiently to prevent any gravel, pebbles or other small objects from jamming and damaging the machine. Provision is made, however, for releasing any one or all of the springs and to permit them to swing inwardly out of the way of the bucket whenever an unusual obstruction is encountered.

For this purpose each spring 16 rests at its forward end on a roller 21 mounted in the forked end 22 of a clevis 23 which extends longitudinally of the housing 14 and is longitudinally slidable 85 therein. The forked portion 22 of the clevis is supported by links 24 from a pivot pin 25 extending transversely of the housing while the extremity of the clevis stem 23 projects out of the housing and is supported by links 26 from a pivot pin 27 mounted in an ear 28 formed on the outside of the housing. A stiff coil spring 29 surrounding the stem of the clevis 23 bears against the shoulder of the forked portion 22 of the clevis and normally 90 holds the roller 21 projected as far as possible beneath the front end of the spring. The rearward movement of the clevis is limited by the engagement of the links 26 with seats 30 formed on the outside of the housing.

The lower side of the housing is closed by a U-shaped cover 31 secured thereto by screws or the like so that the spring 29 is protected against dirt and mud.

The front end of each spring which normal-

ly rests on the corresponding roller 21 is rounded, as at 32, and the distance of this rounded face from the pivot 18 is slightly less than the distance of the center of the roller 21 from this pivot. As a consequence, when an unyielding object engages the curved end 19 of the spring, exerting an excessive force tending to swing the spring about the pivot 18, the pressure exerted by the rounded face 32 against the roller 21 is in a line slightly to the rear of the axis of the roller, and when this pressure is sufficiently great the resistance of the spring 29 will be overcome, the clevis 23 and the roller 21 will be forced forwardly and the spring 16 will be released. The clevis 23 and roller 21 may therefore be regarded as a spring held latch which normally holds the cleaner in the position shown, but automatically releases the same when an unyielding 20 obstruction is encountered. At such time, the curved end 19, will be permitted to swing inwardly and relieve the strain. This will prevent breakage of the cleaner, and as soon as the bucket passes beyond the spring 16 the latter may be manually returned to its normal position.

From the foregoing description it will be observed that collectively the springs 16 come in close proximity to all parts of the interior 30 surface of each bucket as it passes dumping position. It makes no difference therefore how sticky the material may be, practically all of it will be removed from the bucket each time the latter passes dumping position, leaving the surface of the bucket comparatively 35 clean. The cleaner therefore is absolutely positive in its action, with the single exception that when a condition arises which would otherwise cause damage to the machine, the 40 spring scraper is automatically released. It may, however, be manually restored to normal position immediately thereafter and the digging operation may be continued without any appreciable interruption.

While I have shown and described in detail what appears at present to be the most desirable embodiment of the invention, it is, of course, to be understood that various modifications may be made therein without departing materially from the scope of the appended claims.

What I claim is:

1. The combination with a series of travelling buckets, of one or more leaf springs, 55 each comprising a plurality of leaves bound together and having one end free, with the free extremity of each successive leaf projecting beyond the preceding leaf, and means including a resiliently held latch member for normally holding the same in such a position that the free extremity of the longest leaf passes through each bucket during the travel thereof and comes into close proximity to the bottom of said bucket.

2. The combination with a series of travel-

ling buckets, of one or more leaf springs, each comprising a plurality of leaves curved outwardly at one end, said end being free, and means including a resiliently held latch member for normally holding the spring in such 70 a position that its outwardly curved free extremity comes into close proximity to the interior surface of each bucket during the travel thereof.

3. The combination with a series of travelling buckets, of one or more leaf springs, each comprising a plurality of leaves bound together and curved outwardly at one end, said end being free with the outwardly curved extremity of each successive leaf projecting beyond the preceding leaf, and means including a resiliently held latch member normally holding the spring in such a position that the curved extremity of the longest leaf comes into close proximity to the interior surface of each bucket during the travel thereof. 75

4. The combination with a series of travelling buckets, of one or more cleaning members, each comprising a spring having a plurality of leaves bound together, with the extremity of each successive leaf projecting beyond the preceding leaf, means normally holding said member in such a position that the extremity of the longest leaf comes into close proximity to the interior surface of each 90 bucket during the travel thereof, and a spring normally controlling the position of said holding means and automatically yieldable to permit the holding means to release the cleaning member so that the latter may swing freely away from the bucket, when struck by an unyielding object. 95

5. The combination with a series of travelling buckets, of one or more cleaning members, each comprising a spring having a plurality of leaves bound together and curved outwardly at one end, means normally holding said member in such a position that its outwardly curved extremity comes into close proximity to the interior surface of each bucket during the travel thereof, and a spring normally controlling the position of said holding means and automatically yieldable to permit the holding means to release the cleaning member so that the latter may swing freely away from the bucket, when struck by an unyielding object. 105

6. The combination with a series of travelling buckets, of one or more cleaning members, each comprising a spring having a plurality of leaves bound together and curved outwardly at one end, with the curved extremity of each successive leaf projecting beyond the preceding leaf, means normally holding the cleaning member in such a position that the curved extremity of the longest leaf comes into close proximity to the interior surface of a bucket during the travel thereof, and a spring normally controlling the position of said holding means and auto- 115

matically yieldable to permit the holding means to release the cleaning member so that the latter may swing freely out of operative relation to said bucket, when struck by an unyielding object.

7. The combination with a series of travelling buckets, of a cleaning member comprising a spring having a plurality of leaves, said spring being pivotally supported intermediate its ends, holding means for said spring, a spindle on which the holding means is mounted, parallel links supporting the spindle, and resilient means acting against said holding means to cause the latter to normally engage and hold one end of the leaf spring in a fixed position while the other end projects into close proximity to the interior of each bucket during the travel thereof, said resilient means being automatically yieldable to release the cleaning member and permit it to swing freely about its pivot when struck by an unyielding object.

8. In a bucket cleaner, the combination of a longitudinally disposed intermediately pivoted bucket cleaning member, a latch member, parallel links supporting said latch member, yieldable means normally projecting said

latch member partially beneath one end of said cleaning member to hold it against movement about its pivot, said end of the cleaning member being rounded and so disposed as to exert pressure obliquely against the end of the latch member, tending to force back the latch member and release said cleaning member when an unyielding object encounters the other end of the said cleaning member.

9. In a bucket cleaner, a support, a member pivoted between its ends to said support with one end bearing against the support and having a rounded face, a latch member, parallel links supporting said latch member, yieldable means acting on said latch member to project one end thereof in front of the rounded face of the pivoted member to hold the latter in its normal position against said support, said rounded face being so disposed as to exert pressure tending to retract the latch and release the pivoted member when an unyielding object encounters the other end of said pivoted member.

In testimony whereof, I have hereunto signed my name to this specification.

CHARLES L. GEORGE.
